[57] **ABSTRACT**

A high voltage high current vacuum fuse having a pair of conductive members supported in a spaced relation within a dielectric housing and shielded by a condensation shield, the conductive members being spaced to provide a gap of sufficient length to interrupt current and being interconnected by a fusible link, the fusible link being of a minimum diameter to provide a minimum volume of fusible material and the conductive members having heads of maximum cross sectional area to provide condensation surfaces of large mass to produce immediate condensation of the vapor produced on fusing of the link. One or both of the conductive members can be biased to increase the gap on fusing of the link.

FUSED VACUUM INTERRUPTER

Related Application

This application is a division of my copending U.S. application Ser. No. 191,205 and entitled "Vacuum Interrupter", filed on Oct. 21, 1971 which is a continuation-in-part of my application Ser. No. 18,868 entitled "Vacuum Fuse", filed on Mar. 12, 1970 and now abandoned.

BACKGROUND OF THE INVENTION

Vacuum fuses generally have been provided with a fusible link which is connected to conductive members located at each end of the fuse. The fuses must be of sufficient cross section to carry normal current. The volume of the fuse because of its length is substantially large and on interruption will produce a substantial amount of vaporized material resulting in an increase in pressure between the contacts which might be even higher than atmospheric. Condensation shields have been provided to promote rapid condensation of vaporized material and to mask the inside surface of the dielectric housing so that the condensed material cannot be deposited on the inside surface of the housing. However, it has been found that due to the large mass of the fusible element, the momentary increase in pressure produced on fusing of the element is large enough to produce an arc plasma sufficient to support an arc long enough to cause an explosive condition in the fuse.

SUMMARY OF THE INVENTION

The vacuum fuse of the present invention minimizes the amount of fusible material in the fuse link while still providing a sufficient gap between the conductive members to interrupt current. This is achieved by providing a pair of conductive members having a substantially large mass within a dielectric housing with the surfaces of the conductive members located in a spaced relation within the housing and connected by a single fusible link of short length and minimum cross section. The large mass of the conductive members provides a cooling surface immediately adjacent the fusible link for condensing the vaporized fused material. The immediate condensation of the vaporized fused material minimizes the possibility of establishing an arc plasma between the conductive members which could prolong the time of arc interruption.

DRAWINGS

FIG. 1 is a side view in section of one form of the invention having a single fusible link interconnecting a pair of stationary conductive members; and

FIG. 2 is a side view in section of another embodiment of the invention showing a single fusible link interconnecting the stationary conductive members and movable members.

DETAILED DESCRIPTION

The vacuum fuse 10 of the invention shown in FIG. 1 is a one-shot type fuse generally used in high current high voltage networks. The fuse 10 generally includes a hollow cylindrical housing or casing 12 formed of porcelain, glass or glass ceramic. A cylindrical condensation shield 14 is mounted within the casing 12 by means of flanges 15 secured or embedded in the housing 12. A pair of stationary conductive members 16 are supported in a spaced relation within the housing 12 by

means of end walls 18. The outer edges 19 of the end walls 18 are hermetically sealed to the end of the housing 12 and the inner edges 21 are hermetically sealed to the conductive members 16. The space or gap between the conductive members is closed to complete the circuit through the conductive members 16 by means of a fusible element or link 20. The condensation shield 14 and end walls 18 can be formed of a metallic material such as Kovar.

The housing 12 is evacuated by means of a tube 22 sealed in an opening 24 provided in one of the end walls 18. Air is withdrawn from the housing by any conventional means to produce a vacuum and tube 22 is crimped to seal the housing 12. It is generally understood in a vacuum interrupting device that the pressure should be reduced sufficiently to place the gas in a state of molecular flow. Molecular flow refers to the Knudsen number determined by the ratio of the mean free path L_m of gas molecules to the radius R of a cylindrical tube. When the mean free path L_m to R is larger than 1, the flow is considered to be molecular.

The gaseous medium in vacuum interrupting devices is usually in the molecular flow range. However, when high currents are interrupted the pressure of the gas in the arc column confined in the space between the contacts might be even higher than atmospheric. This high pressure must be reduced very rapidly as the gas diffuses into the volume of the enclosure. Since the arc should not last any longer than half a cycle, the pressure of the arc column between the contacts should be kept below the limit that permits interruption. This limit is generally recognized to be 10^{-4} torr.

In accordance with the invention, the cross section of the ends or heads 26 of the conductive members 16 are large with respect to the cross sectional area of the fusible element 20. In this regard, the volume of the fusible element 20 is kept to a minimum with respect to the volumetric space between the surfaces of the ends 26 of the conductive members 16 in order to interrupt current in a 60 cycle system as soon as the current passes through zero. It should be noted that if the current continues to arc for one or more cycles, an explosive condition will exist within the fuse as a result of the rapid increase of pressure within the fuse.

The volume of the fusible link is determined by the cross sectional area and the length of the link. The cross sectional area determines the ampere continuous and the length determines the withstand voltage after break. The rate of condensing of the metal vapor on fusing of the link determines the interruption ability, i.e., ampere fault and voltage. Therefore, to increase the rate of condensing of the metal vapor, the cross sectional area of the ends of the conductive members must be increased and/or the amount of vaporized material decreased.

For example, in a 15KV system the fusible link 20 should have a length of approximately $\frac{1}{2}$ inch. The cross sectional area of the ends 26 of the conductive members 16 should be made at least 5 times larger than the cross sectional area of the fusible link. The cross sectional area is determined by the anticipated continuous current.

With this arrangement, a large cooling surface 26 is provided on each side of the fusible element 20. When a short circuit current occurs, the fusible element 20 will vaporize and will immediately condense on the surface of the ends 26 of the conductive members 16. Any

vaporizable material which diffuses outwardly from the space between the ends 26 of the conductive members 16 will be condensed on the shield 14. The immediate condensation of the vaporized fuse material prevents the creation of arc plasma sufficient to allow the arc to continue for more than $\frac{1}{2}$ cycle.

In order to achieve higher KV levels, the arc gap should be increased between the conductive members without increasing the length of the fusible element 20. Referring to FIG. 2, another embodiment of the invention is shown which provides an increased gap for higher KV's. As seen in FIG. 2, the fuse 40 includes a dielectric housing 42 and a condensation shield 44 secured to the housing by a flange 45. A stationary conductive member 46 is supported on one of the end walls 48 and a movable conductive member 50 is supported by a tubular member 52 provided on the other end wall 54. The outer edges 47 of the end walls 48 are hermetically sealed to the housing 42 and the inner edges 55 of the end wall 54 are hermetically sealed to the other end of the housing 42. The conductive members 46 and 50 have their inner ends 56 spaced a predetermined distance apart. The circuit through the conductive members 46 and 50 is completed by means of a fusible element or link 58. The relationship between the cross sectional area of the ends or heads 56 and 57 of the conductive members 46 and 50, respectively, and the cross sectional area of the fusible link 58 is determined as described above.

However, even though the KV rating is larger, the length of the fusible element is maintained the same. This is accomplished by increasing the distance between the conductive members 46 and 50. In this regard, the movable conductive member 50 is mounted for axial movement in the tubular member 52 which is secured to the end wall 54. The member 50 is biased away from the member 46 by means of the spring 60 which is connected at one end to the movable element 50 and at the other end to the end wall 54. The conductive member 50 is connected into the circuit by means of a flexible electrical conductor 62 which is connected to an external contact 64 provided in the end wall 54.

On fusing of the link 58, the spring 60 will move the conductive member 50 away from the conductive member 46 toward the end wall 54. This movement of the conductive member 50 provides a double function

in that the end 57 of the member 50 provides a large mass to condense the vaporized fuse material and increases the gap between the ends 56 and 57 of the conductive members 46 and 50. Although a spring has been shown for biasing the conductive member 50 towards the end wall 54, other types of biasing means can be used.

I claim:

1. A fusible vacuum interrupter for protecting a high voltage electric circuit, said interrupter comprising:
a sealed dielectric housing,
two electrically conductive members supported in closely spaced relation in said housing, one of said members being movable within said housing,
a fusible element having a length of approximately $\frac{1}{2}$ inch bridging the space between said members, said members having contact surfaces having cross sectional areas greater than 5 times the cross sectional area of the fusible element,
and means for biasing said one movable member away from said other member.
2. A high voltage vacuum fuse comprising:
a housing formed from a dielectric material,
a pair of electrically conductive members supported in a spaced relation within said housing and being operatively connected to a high voltage circuit, one of said conductive members being mounted for movement within said housing,
means for biasing said one of said members away from said other member to increase the gap between the members on fusing of said element,
a fusible element interconnecting said electrically conductive members,
said conductive members each having cross sectional areas greater than five times the cross sectional area of the fusible element whereby said members are separated on fusing of said element to provide a sufficient gap for arc interruption and a large mass for condensing fusible element material on arc interruption.
3. The vacuum fuse according to claim 2 wherein said biasing means includes a spring operatively connected to move the movable member away from the stationary member on fusing of the link.
